UNITED STATES PATENT OFFICE

2,159,100

BRAKE BEAM STRUT

David Paterson, Lindsay, Ontario, Canada

Application July 12, 1937, Serial No. 153,096

7 Claims. (Cl. 188—232)

The principal objects of this invention are to provide a brake beam strut of the rotatably adjustable type which will have the minimum number of parts and which will be firmly and positively locked in either a left or right hand position according to requirements.

The principal features of the invention reside in the novel construction of the strut member having a portion formed to embrace the brake beam and to be adjustably interlocked therewith and in the provision of a relatively adjustable portion for engaging the brace rod and adapted in certain cases to co-operate with the brace rod and with the strut to positively lock the strut in adjusted positions.

In the drawing, Figure 1 is a plan view of a brake beam assembly showing one form of my invention applied thereto.

Figures 2 and 3 are side elevational and longitudinal sectional views respectively of the strut shown in Figure 1.

Figures 4 and 5 are plan and longitudinal sectional views taken at right angles to Figures 2 and 3 respectively.

Figures 6 to 9 are vertical part sectional elevational views illustrating the manner in which the strut may be swung to either a "left" or "right" hand position in relation to the beam.

Figure 10 is a perspective detail illustrating a special interlocking rod-engaging member and a specially notched bore in the end of the strut for co-operation therewith.

Figure 11 illustrates a further modified form of adjustable connection between the rod-engaging member and strut to provide for selective angular adjustment.

Figure 12 is a further modified form of construction in which the beam-embracing end of the strut is provided with diagonal or intersecting recesses to receive and interlock with the edges of the beam flanges.

Figure 13 is an enlarged perspective view illustrating a preferred form of key for locking the strut to the beam.

It has been heretofore proposed to provide rotatable brake beam struts which could be swung to either a left or right hand position in accordance with the location required of same in service, but such structures have either been of such a complicated and expensive nature as to discourage their use, or a complicated type of locking means was required in order to retain the strut in the angular position to which it had been adjusted.

The present invention proposes a very desir-

able form of strut which is of simple but effective construction, permitting the desired adjustment with the minimum number of parts.

In the form of the invention illustrated in Figures 1 to 9 the strut 1 which preferably comprises a casting of suitable metal, is formed with an integral head comprising an inner flange 2 and an outer flange 3 spaced therefrom and connected at the ends by integral portions of inwardly converging form, as indicated at 4 and 5 which are adapted to limit the angular swinging movement of the strut about the centering bolt 6 by engagement with the opposite flanges 7 of the brake beam 8 as best illustrated in Figures 6 and 7.

The centre bolt 6 passing through the web of the beam 8 and centrally through the head flange 3, serves not only to prevent shifting of the strut longitudinally of the beam, but also to permit the aforesaid rotative adjustment.

A notch 9 cut in the face of the head flange 2 is shown extending across the head and the opposite ends thereof are adapted to register respectively with notches 10 or 11 cut angularly in the edge portion of one of the beam flanges 7 when the strut is swung to a "left" or "right" hand position and a key member 12 is adapted to be inserted in the aligned notches 9 and 10 or 9 and 11 to positively lock the struts in either position.

The key member 12 may advantageously be split longitudinally so that one portion will be accommodated in the head slot 9 while the other portion due to the angular disposition of the slots 10 and 11, will, on striking the lower flange 1 of the beam, be deflected angularly to effectively retain the key against accidental displacement.

The strut member is slotted transversely at 13 to receive the brake lever 14 pivotally mounted on the transverse bolt 15. The end of the strut opposite the head is here shown provided with a key hole slot 16 and a saddle portion 17 is transversely grooved to embrace the brake rod 18 and is provided with a stem portion 19 having a locking lug 20 adapted to be inserted through the key hole slot and to be locked to the head on rotation of the saddle member 17, as best illustrated in Figure 3, so that the strut member and saddle are relatively rotatably adjustable, while retaining their interlocked relation.

In the form of the invention illustrated in Figure 10, the rod-engaging saddle member 17' carries a stem portion 19' having a key portion 20' and the end of the strut has a bore 21 to snugly receive and centre the stud 19' and the bore is 55

formed with peripherally spaced locking notches 21' which form with the centre bore 21 key hole slots adapted to selectively receive the locking key 20' to positively lock the strut in either a "left" or "right" position, since it will be apparent that by thus interlocking the saddle member 17' with the strut, the interlocking of the brake rod 18 with the transverse groove of the saddle member 17' will preserve the adjustment 10 and prevent the strut from swinging to a different position in service.

In the form shown in Figure 11 the inter-engaging portions of the brake rod saddle 17' and strut 1 are shown as radially serrated in a peripheral path, as indicated at 22 and since the serrations or teeth may be made comparatively fine, this form of locking connection will permit of a wider range of adjustment and it will be further observed that it will permit the brake 15 strut to be rotatably adjusted or even swung 20 from a "left" to a "right" position should such be required by simply slackening off the brake rod nuts 18', after which they may be tightened to rigidly retain the serrated members in their adjusted relation.

In the alternative modification illustrated in Figure 12 the head flange 2 of the brake strut is shown having molded therein diagonal or transversely intersecting grooves 23 which are spaced parallelly apart to correspond with the spacing of the flanges 7 of the brake beam 8 and are adapted to receive the edge portions of the flanges to positively interlock therewith in either a "left" or "right" position and where this form of interlock is employed the flange 3 may be spaced a slightly greater distance from the flange 2 in order to permit the edges of the brake beam flanges 7 to be disengaged therefrom, permitting the strut to be swung to the desired position should it be necessary after assembly to alter the position of the strut and after positioning, the tightening of the brake rod nuts 18' will draw the flange edges into firm seating and interlocking contact with the grooves 23 or 24.

What I claim as my invention is:

1. In a brake assembly having a beam and truss rod, a strut member interposed between said beam and truss rod having a head portion flanged to embrace the beam in selecting "left" or "right" hand positions, said head and beam having notches adapted to register when the strut is positioned in either a "left" or "right" hand position for the reception of a locking member.

2. In a brake assembly having a brake beam

and truss rod, a strut member having a flanged head rotatably adjustable on the brake beam and having a notch formed therein, a pair of notches formed in the adjacent flange of the brake beam adapted to register with the aforesaid notch selectively when the strut has been rotated to either a "left" or "right" hand position, and means for removable insertion into said aligned notches to lock the strut to the brake beam. 5

3. A brake beam strut having in combination a head for rotatable mounting on the brake beam and having a key hole slot in the other end, and a saddle member transversely grooved to embrace a truss rod and having a stem portion formed to enter said key hole slot and to interlock with 10 said strut. 15

4. A brake beam strut for insertion between a brake beam and truss rod and having a head rotatably embracing the brake beam, the other end of said strut having an axial bore formed with peripherally spaced locking notches, and a rod-engaging member formed with a stem to snugly enter said bore and having a locking key adapted to selectively engage said locking notches to lock the strut in rotatably adjusted positions. 20

5. A brake beam strut for insertion between a brake beam and truss rod, said strut having a head rotatable on the brake beam to "left" or "right" hand position selectively, and means for locking said strut in either of its rotatably adjusted positions including a rod-engaging member adjustable relative to said strut and having selective locking engagement therewith. 25

6. Means as claimed in claim 5 in which said rod-engaging member is transversely grooved to 30 interlock with said rod and has a serrated seating portion for interlocked engagement with a serrated seating portion of said strut. 35

7. In a brake assembly having a flanged beam and a truss rod, a reversible strut for interposing therebetween, and means co-operative with said strut having positive non-rotative locking co-operation simultaneously with the beam and strut at one end and with the rod and strut at the other end in both "left" and "right" positions, 40 said means being free of bolt connections and including an integral head portion having a rotatable mounting directly on the flanges of the beam from one locking position to another and selectively engageable toothed and notched locking means interposed between the said other end 45 and the rod. 50
